UNITED STATES PATENT OFFICE

EDWARD F. RAYMOND, OF LOS ANGELES, CALIFORNIA, ASSIGNOR TO JOHN GRANT, OF LOS ANGELES, CALIFORNIA

UNDERREAMER

Application filed January 24, 1931. Serial No. 510,978.

This invention has relation to expansive reamers which are most used for underreaming in deep wells. The general object of the invention is the provision of a simple, strong structure for an underreamer of the type which is expanded by relative rotation.

The various features and accomplishments, and the corresponding objects of the invention will be best understood from the following detailed description of a preferred and illustrative embodiment rather than from general preliminary description. I proceed therefore to such a detailed description, reference for this purpose being had to the accompanying drawings, in which:

Figure 1 is a vertical central longitudinal section showing my underreamer in contracted position;

Fig. 2 is a similar view showing the expanded position;

Fig. 3 is a cross section on line 3-3 of Fig. 1;

Fig. 4 is a cross section on line 4-4 of Fig. 2; and

Fig. 5 is a cross section on line 5-5 of Fig. 1.

The central and relatively rotatable mandrel is designated by the numeral 10, and a surrounding tubular slotted body by numeral 11. The tubular body 11 is provided with a plurality of longitudinally extending cutter receiving slots 12 in which the cutters 13, here illustrated as three in number, are mounted. The cutters are here shown as composite cutters, made up of cutter carriers or bars 14, and roller cutters 15; but these cutters may be taken as typical of any other cutter make-up, as the nature of the cutters may vary according to the formation being operated upon. The cutters are made to fit slidably in slots 12, so as to move in and out between the contracted and expanded positions; and at their upper and lower ends they have extensions 14a adapted to be overhung by certain parts which will be hereafter described.

Mandrel 10 is provided with cutter expanding cams 20 which, by relative limited rotation of the mandrel, are adapted to cam the cutters out to their expanded positions.

It is desirable that the cutters be cam- and therefore mandrel-supported at or near both ends, if it is desirable that the cutters be expanded throughout their lengths. I have shown such a design in the drawings and have illustrated two sets of cams 20 located near the upper and lower ends of the cutters and designed to expand equally the upper and lower ends. If it is desired to expand one end of the cutters more than the other, or desired, for instance, to expand only the upper ends of the cutters, one set of cams (e. g. the lower set) may be made of lesser radial throw, or eliminated altogether. In any case, the cams being integral parts of the mandrel, the cutters bear inwardly upon the internal mandrel for support at both ends. And the cams may be made of any length desired along the mandrel; so that the cutters are supported throughout any proportion of their lengths desired.

The mandrel also carries stop lugs which, by contact with the body, limit relative rotation of the mandrel. I have preferably shown two such sets of stop lugs, near the upper and lower ends of the mandrel. The upper set, as here illustrated, comprises three stop lugs 25 on the mandrel, and three corresponding recesses or grooves 26 in the inner walls of the body at the longitudinal position of the stop lugs. These recesses are of proper circumferential extent to allow the necessary limited relative rotation of the mandrel to expand and contract the cutters. The position shown in Figure 3 is the contracted position; relative right-handed rotation of the mandrel from that position throws the mandrel and its cams 20 to the expanded position where the cams are behind the cutters, supporting them.

Directly below the stop recesses 26 the body has an internal bore 30 which is of a diameter large enough to accommodate the cams and is of substantially the same diameter as the bottoms of the recesses 26. Being of this diameter, this bore 30 not only accommodates the cams but also can pass the lower mandrel stop lugs 25a which are situated near the lower end of the mandrel. These lower stop

5 lugs, here shown as two in number, play in two recesses 26a, these lugs and recesses having the same stopping function as the ones at the upper end of the mandrel. In assembling the tool, the lower stop lugs can pass through the upper stop recesses 26 and then on down through the bore 30 into the stop recesses 26a. It is desirable to provide stops between the mandrel and body at both upper and lower 10 ends so as to provide great strength of rotational connection between the mandrel and body. Rotary motion is applied to the tool through the mandrel, which is connected at its upper end with the rotary drill stem. The 15 reaming cutters are, of course, mounted in, or carried by the body. The lower drill bit 35 is also mounted on, and given rotary motion through, the body. It is therefore desirable that rotational connection between the mandrel and body be strong.

20 At the lower end of the mandrel I provide a collar 36 screw-threaded upon the mandrel. This collar 36 presents an upwardly facing bearing shoulder 37 which bears upwardly 25 against the lower end of body 11 and prevents relative downward movement of the body. The drill bit 35 (or a sub which connects with the drill bit) has in its upper end a recess 38 enclosing the lower end of the mandrel and the collar 36; and this member 35 30 also has a screw-threaded box 39 which is screw-threadedly attached to the lower end of the body. The lower end of collar 36 provides a downwardly facing bearing surface to give a good downward thrust bearing upon the drill bit; and if desired this bearing face may be provided with rolling bearings 40.

35 At its upper end mandrel 10 is provided with a head which is here shown in the form 40 of a sub 50 screw-threaded to the upper end of the mandrel at 51, and adapted at its upper end for connection with the drill stem. The lower end of this sub overhangs the mandrel and the upper end of tubular body 11, providing a downwardly facing thrust bearing surface to bear down against the upper end of the tubular body. And if desired rolling bearings 52 may be inserted at this bearing surface. The sub or head 50 carries a downwardly 45 extending sleeve 55, which sleeve depends over the upper end of the body and downwardly over the upper ends of cutter-receiving slots 12, thus overhanging the upper extensions 14a of the cutters. The sleeve is 50 here shown as screw-threaded at 56 to the sub for convenience of removal. In function, the sleeve may be an integral part of the sub, and the sub may likewise be an integral head on the upper end of the mandrel. How- 55 ever, it is convenient in manufacture to make the sub a separate piece.

60 At the lower ends of cutter-receiving slots 12 the body has upwardly projecting walls 60 which overhang the lower ends of the slots, 65 and confine the lower projections 14a of the

cutters. Preferably, in order to cause cutter contraction when the mandrel is in contracted position, I provide small springs 61 which bear between the cutter extensions and the overhanging wall 60 and sleeve 55.

70 To disassemble my reamer it is only necessary to remove the bit member 35 from the lower end and then remove collar 36, when the mandrel may be withdrawn longitudinally from the body, carrying with it the 75 sleeve 55. The cutters may then either be removed outwardly through the slots or, in the design here shown, may be removed inwardly through the interior of the body.

80 I claim:

1. In an expansive reamer, the combination of a tubular slotted body, cutters movable inwardly and outwardly in the body slots, a relatively rotatable mandrel extending longitudinally in the body and having cams acting on the cutters to move the cutters out by virtue of relative mandrel rotation, the body having at one end of the slots a wall overhanging the cutter ends, and a sleeve mounted on the mandrel and overhanging the 85 cutter ends at the other end of the body slots.

2. In an expansive reamer, the combination of a tubular slotted body, cutters movable inwardly and outwardly in the body slots, a relatively rotatable mandrel extending longitudinally in the body and having cams acting on the cutters to move the cutters out by virtue of relative mandrel rotation, a sub connected with the upper end of the mandrel and having a downwardly facing shoulder confining the body against relative upward movement, a sleeve mounted on the sub and overhanging the body downwardly to overhang the upper ends of the body slots and the upper ends of the cutters, means at the lower end of the mandrel confining the body against relative downward movement on the mandrel, and the body having at the lower ends of the slots a wall overhanging the lower ends of the cutters.

105 3. In an expansive reamer, the combination of a tubular slotted body, cutters movable inwardly and outwardly in the body slots, a relatively rotatable mandrel extending longitudinally in the body and having cams acting on the cutters to move the cutters out by virtue of relative mandrel rotation, the body having at one end of the slots a wall overhanging the cutter ends, and a sleeve mounted on the mandrel and overhanging the cutter ends at the other end of the body slots, and springs between the overhanging wall and sleeve and the cutters tending to move the cutters inwardly.

115 4. In an expansive reamer, the combination of a tubular slotted body, cutters movable inwardly and outwardly in the body slots, a relatively rotatable mandrel extending longitudinally in the body and having cams acting on the cutters to move the cutters 120

125

130

out by virtue of relative mandrel rotation, a sub connected with the upper end of the mandrel and having a downwardly facing shoulder confining the body against relative upward movement, a sleeve mounted on the sub and overhanging the body downwardly to overhang the upper ends of the body slots and the upper ends of the cutters, means at the lower end of the mandrel confining the body against relative downward movement on the mandrel, and the body having at the lower ends of the slots a wall overhanging the lower ends of the cutters, and springs between the cutters and the overhanging wall and sleeve tending to move the cutters inwardly.

5. In an expansive reamer, the combination of a tubular slotted body, cutters movable inwardly and outwardly in the body slots, a relatively rotatable mandrel extending longitudinally in the body and having cams acting on the cutters to move the cutters out by virtue of relative mandrel rotation, a sub connected with the upper end of the mandrel and having a downwardly fac-

10 ing shoulder confining the body against relative upward movement, a sleeve mounted on the sub and overhanging the body downwardly to overhang the upper ends of the body slots and the upper ends of the cutters, the body having at the lower ends of the slots a wall overhanging the lower ends of the cutters, a collar screw-threaded on the lower end of the mandrel and having an upwardly facing shoulder confining the body against downward movement, a bit screw-threadedly attached to the lower end of the body and enclosing the collar on the lower end of the mandrel, the collar having a downwardly facing bearing shoulder to take up-

15 ward thrust from the bit.

6. In an expansive reamer, the combination of a tubular slotted body, cutters movable inwardly and outwardly in the body slots, a relatively rotatable mandrel extending longitudinally in the body and having cams acting on the cutters to move the cutters out by virtue of relative mandrel rotation, the interior of the body having an enlarged cam receiving bore and a grooved wall surface at

20 the upper end, the mandrel having stop lugs adapted to operate in the grooved portion of the body to limit relative rotation of the mandrel, and the mandrel cams adapted to pass through the grooves into the body bore.

7. In an expansive reamer, the combination of a tubular slotted body, cutters movable inwardly and outwardly in the body slots, a relatively rotatable mandrel extending longitudinally in the body and having cams acting on the cutters to move the cutters out by virtue of relative mandrel rotation, the interior of the body having an enlarged cam receiving bore and a grooved wall surface at the upper end, the mandrel having

25 stop lugs adapted to operate in the grooved

portion of the body to limit relative rotation of the mandrel, and the mandrel cams adapted to pass through the grooves into the body bore, a sub connected with the upper end of the mandrel and having a downwardly fac-

30 ing shoulder confining the body against relative upward movement, a sleeve mounted on the sub and overhanging the body downwardly to overhang the upper ends of the body slots and the upper ends of the cutters, the body having at the lower ends of the slots a wall overhanging the lower ends of the cutters, a collar screw-threaded on the lower end of the mandrel and having an upwardly facing shoulder confining the body against downward movement, a bit screw-threadedly attached to the lower end of the body and enclosing the collar on the lower end of the mandrel, the collar having a downwardly facing bearing shoulder to take up-

35 ward thrust from the bit.

In witness that I claim the foregoing I have hereunto subscribed my name this 11th day of December, 1930.
